UNITED STATES PATENT OFFICE.

AUGUSTO BROCK, OF BUENOS AYRES, ARGENTINE REPUBLIC.

AIR-ENGINE.

SPECIFICATION forming part of Letters Patent No. 434,422, dated August 19, 1890.

Application filed February 3, 1890. Serial No. 338,997. (No model.)

To all whom it may concern:

Be it known that I, AUGUSTO BROCK, a subject of the King of Prussia, Germany, residing at Buenos Ayres, Argentine Republic, 5 have invented certain new and useful Improvements in Air-Engines, of which the following is a specification.

This invention relates to certain improvements in air-pumps or exhausters and condensers; and the invention consists in certain novel features of construction and in combinations of parts, more fully described hereinafter, and particularly pointed out in the claims.

15. In the accompanying drawings, Figure 1 is a side view thereof. Fig. 2 is another side view at right angles to the former. Fig. 3 is an elevation of a modification.

Upon a suitably-supported horizontal shaft 20 *a* is mounted at one end thereof a vane or fly *b*, while the other end of the same shaft carries a crank *d*, to which is connected a rod *e*. The rod *e* is jointed with the upper end of another rod *f*, the joint being guided by the 25 links *g' g' g'*. The links *g' g' g'* are attached to the frame, as shown. The lower end of the rod *f* is fixed to an india-rubber cap or hood *h*, having a somewhat semi-spherical shape, and secured at its lower part to a tapered closed vessel *i*, of sheet-steel or other suitable metal. At the lower end of this vessel is fixed, laterally, a casting *k*, furnished with a hole *k'*, communicating with the inside of the vessel. The front or outside surface of this casting *k* is ground smooth or 30 faced up, and against the same moves an oscillating plate *m*, which is pivoted to turn upon a pin or pivot *m'*. The plate *m* is terminated by a bar *m²*, which is shaped to that of the vessel *i* and the semi-spherical cap or hood *h* when expanded. The bar *m* carries 35 at its upper end a slotted bar or guide *m³*. Within this guide slides a block *n*, which is connected by means of an extension *o* of the crank *d*.

The sliding plate *m* is provided with two holes or ports and short tubes *p p'*, which communicate alternately with the opening *k'* in the casting *k*, and the vessel *i*, so that

when the plate *m* is set oscillating to and fro 50 from the rotary motion of the cranks *d* and *v* by the action of the wind against the vane or fly *b* the hood *h* is alternately collapsed and expanded. When the hood is collapsing, the air contained in the vessel *i* is compressed 55 and expelled through the port *k'* and pipe *p'*, in order to be conveyed to a reservoir or the like, while when the same hood *h* is expanding air is again drawn in through the pipe *p* and the hole or port *k'* into the vessel *i*. The pipe 60 *p'* may be connected with a storage-reservoir for the compressed air by means of a suitable india-rubber pipe or hose. The hood *h* is made of fairly strong india-rubber, so that when collapsed, as shown in Fig. 2, it has a 65 tendency to return to its normal position by reason of the elasticity of the india-rubber.

The air-pump may be simplified by substituting for the piece *k*, with the sliding plate *m*, a chest or shell, with an exhaust and forcing valve or tap, as shown in Fig. 3. In the valve-chest *r* the expansion of the hood *h* causes air to be drawn in at *r'*, and its collapse causes air to be expelled at *r²*.

It is evident that various changes might 75 be made in the form and arrangements of the parts described without departing from the scope and spirit of my invention; hence I do not wish to limit myself to the precise construction herein set forth.

Having now particularly described and ascertained the nature of this invention, and in what manner the same is to be performed, I declare that what I claim is—

1. In combination, the air-tight receiving-chamber having the flexible dome top, and the casting in its lower portion forming a port, the vertical rod secured to said top, the drive-shaft provided with a crank connected with said rod, and the swinging valve-plate secured to said casting having the upwardly-extending arm loosely connected to said crank to be rocked thereby, substantially as described.

2. The combination, with the receiving-vessel having a port and the collapsible flexible hood or top, of the swinging plate having two ports adapted to alternately register with

said port of the vessel and provided with the
extended arm and guide, and the crank-shaft
connected to intermittently collapse said
hood, the crank of said shaft having an ex-
tended end provided with a sliding block con-
fined in said guide to rock said plate, sub-
stantially as described.

In testimony whereof I have signed my
name to this specification in the presence of
two subscribing witnesses.

AUGUSTO BROCK.
